BOILER

Ralph C. Brierly, Narberth, Pa.

Application June 24, 1948, Serial No. 34,994

8 Claims. (Cl. 122—240)

(Granted under the act of March 3, 1883, as amended April 30, 1928; 370 O. G. 757)

1

This invention relates to improvements in apparatus and methods of high-rate steam generation, and more particularly pertains to means for producing steam in large quantities albeit using units lighter and more compact than those employed presently.

Conventional boilers used in high-rate steam generation require large furnaces, such furnaces constituting frequently twenty per cent or more of the total boiler weight and occupying at least that percentage of the total space taken up by the entire unit. Present furnaces operate normally at heat releases not exceeding approximately a quarter of a million B. t. u. per cubic foot per hour at full power, although in some installations or at extreme conditions heat releases can rise to a maximum level of no more than one-half of a million B. t. u. per cubic foot per hour. (One type of large and heavy furnace construction employed presently to achieve such level is the ponderous and complicated arrangement used in French boilers of the general Sural type, wherein single boilers or groups of boilers are placed in a heavy shell or separate compartment known as the "vase clos," so that heavy inner and outer casings are required.)

The structures herein disclosed are adapted to develop heat releases of 10 to 20 million B. t. u. per cubic foot per hour. Consequently, the overall furnace volume can be reduced to a fraction of the volume of furnaces now employed. In addition, end gas firing of the entire tube bank augments B. t. u. releases greatly above present figures, also dispensing with furnaces as such.

The primary object of this invention is to provide apparatus and methods of high-rate steam generation whereby substantial reduction in both space and weight requirements is effected by utilizing novel furnace structure.

Another object is to provide apparatus and methods of high-rate steam generation characterized by speeds and concentrations of combustion of an order higher than speeds and concentrations heretofore possible without recourse to large and heavy furnace construction.

Still another object is to provide apparatus and methods of high-rate steam generation whereby such high heat concentrations can be applied to the boiler tubes that lighter and more compact installations, occupying less vertical height and reducing the number and lengths of such tubes materially, can be employed.

Other objects and many of the attendant advantages of this invention will be readily appreciated as the same becomes better understood by

2

reference to the following detailed description when considered in connection with the accompanying drawings, wherein

Fig. 1 is a fragmentary elevation of a furnace, partly in section, showing a preferred embodiment of the invention;

Fig. 2 is a plan view of a bank of the elements shown in Fig. 1;

Fig. 3 is a fragmentary elevation of a furnace, partly in section, showing a modified form of the invention;

Fig. 4 is a side elevation of a bank of the elements shown in Fig. 3;

Fig. 5 is a fragmentary elevation of a furnace, partly in section, showing a further modified form of the invention; and

Fig. 6 is a section taken on the line 6—6 of Fig. 5.

Similar numerals refer to similar parts throughout the several views.

In the preferred embodiment of the invention shown in Figs. 1 and 2, a steam drum 11 extends horizontally, being supported by suitable means not shown. A water drum 13 extends horizontally and parallel to said steam drum, said water drum likewise being supported by suitable means not shown. Water drum 13 is positioned a distance below said steam drum 11, and a plurality of downcomer tubes 15, each having its axis normal to the axes of the said steam and water drums, communicate between said two drums. Tubes 15 are arranged preferably in uniformly spaced relation along the length of said two drums.

A plurality of headers 17 and 18 are cylindrical drums positioned in axial parallelism with and somewhat below the level of drum 13, and a plurality of conduits 19 communicate between said headers and said drum 13. Another plurality of headers 21 and 22, are positioned vertically above headers 17 and 18 respectively. A plurality of conduits 23 communicate between headers 21 and 22 and drum 11.

Bundles of tubes 25 communicate between headers 17 and 21. Said tubes can be straight, except for the end portions thereof that are manifolded into said headers 17 and 21, as shown in Fig. 1, or can be formed into a spiral or coiled configuration to increase total length of each tube of said bundle. Other bundles of tubes 27 communicate between headers 18 and 22. Said tubes 27 can be straight, except for the end portions thereof that are manifolded into said headers 18 and 22, as shown in Fig. 1, or can be formed into a spiral or coiled configuration to

increase total length of each tube of said bundle.

Headers 17 and 21, and their connecting bundle of tubes 25, are enclosed in the casing 29 of a peripheral burner of the type disclosed in U. S. patent application Serial No. 789,261, filed December 2, 1947. Said casing carries a plurality of hollow frusto-conical rings 31, arranged in axial alignment and in spaced relation along the length of said bundle of tubes 25. Combustibles are supplied to said rings through conduits 33 to provide flame propagation over a substantial portion of the length of said casing, around said bundle of tubes 25.

Duct 35 communicates between the exit end of casing 29 and the entrance end of said casing, 15 said duct carrying an economizer 37 proximate said exit end and a blower 39 proximate said entrance end. Alternatively, said duct can be constructed so as to communicate between the exit end of a first casing 29 and the entrance end of an adjacent casing 29, where a bank of such burners is employed, with a duct communicating similarly between the exit end of the last of said casings in said bank and the entrance end of said first casing, to provide a closed series system.

Similarly, headers 18 and 22, and their connecting bundle of tubes 27, are enclosed in such a peripheral burner, as shown in Figs. 1 and 2.

In operation, combustibles are forced into the hollow frusto-conical rings forming the walls of the combustion chamber and out of the apertures provided in the trailing edges thereof. Such combustibles burn in a moving stream surrounding each of the bundles of tubes, with oxidant passing axially through the chamber and oxidant being supplied between said rings. After the gases of combustion pass over the substantially vertical or coiled tubes, such gases exit from the burners, are cooled by passage through the economizer sections, and then are either passed to the atmosphere through a duct (not shown) or used to supplement additional oxidant that is forced into the burners by the blowers. Suitable firing means (not shown) is employed to ignite such combustibles, a preferred type of firing means being that disclosed in pending application Serial No. 551,420 filed August 16, 1944 by Bonvillian, Brierly and Letvin.

Figs. 3 and 4 show a modified form of the invention. Steam drum 41 extends horizontally, being supported by suitable means not shown. A water drum 43 extends horizontally and parallel to said steam drum, said water drum likewise being supported by suitable means not shown. Water drum 43 is positioned a distance below said steam drum 41, and a plurality of bundles of downcomer tubes 45, each bundle having its axis substantially normal to the axes of the said steam and water drums, communicate between said two drums. Said bundles of tubes 45 are arranged preferably in uniformly spaced relation along the length of said two drums.

A plurality of headers 47 and 49 are cylindrical drums positioned in axial parallelism with and somewhat above the level of drum 43, and a plurality of conduits 51 communicate between said headers and said drum 43. Another plurality of headers 53 and 55 are cylindrical drums positioned in axial parallelism with and somewhat below the level of drum 41, said headers 53 and 55 preferably being positioned vertically above headers 47 and 49 respectively. A plurality of conduits 57 communicate between headers 53 and 55, and drum 41.

Tubes 59 communicate between headers 47 and 53. Said tubes can be formed into a spiral or coiled configuration to provide maximum effective length, as shown in Fig. 3, or can be substantially straight. Tubes 61 communicate between headers 49 and 55. Similarly, said tubes 61 can be formed into a spiral or coiled configuration to provide maximum effective length, as shown in Fig. 3, or can be substantially straight.

Headers 47 and 53, and their connecting tubes 59, are enclosed in the casing 29 of a peripheral burner of the type disclosed in U. S. patent application Serial No. 789,261, filed December 2, 1947. Said casing carries a plurality of hollow frusto-conical rings 31, arranged in axial alignment and in spaced relation along the length of each bundle of tubes 59. Combustibles are supplied to said rings through conduits 33 to provide flame propagation over a substantial portion of the length of said casing, around tubes 59.

Duct 35 communicates between the exit end of casing 29 and the entrance end of said casing, 15 said duct carrying an economizer 37 proximate said exit end and a blower 39 proximate said entrance end.

Similarly, headers 49 and 55, and their connecting tubes 61, are each enclosed in such a peripheral burner, as shown in Fig. 3.

A first downcomer 63 communicates between one end of steam drum 41 and the corresponding end of water drum 43, the axis of said downcomer being at a right angle to the axes of said drums. A second downcomer 65 communicates between the other end of steam drum 41 and the other end of water drum 43, the axis of said downcomer being at a right angle to the axes of said drums.

Said downcomers provide supplementary conduits for facilitating circulation between the steam and water drums.

Figs. 5 and 6 show another embodiment of the invention. A steam drum 67 extends horizontally, being supported by suitable means not shown. A water drum 69 extends horizontally and parallel to said steam drum, said water drum likewise being supported by suitable means not shown. Water drum 69 is positioned a distance below said steam drum 67, and a plurality of tubes 71, each having its axis normal to the axes of the said steam and water drums, communicate between said two drums. Tubes 71 are arranged preferably in clusters, said clusters being disposed in uniformly spaced relation along the length of said two drums, as shown in Figs. 5 and 6.

A plurality of downcomer tubes 73 communicate between steam drum 67 and water drum 69 proximate one end of said drums, said tubes 73 being disposed with their axes normal to the axes of said drums. Another plurality of downcomer tubes 75 communicate between said steam and water drums proximate the other end of said drums, said tubes 75 being disposed with their axes normal to the axes of said drums.

A burner manifold 77 is installed at one end of the structure, combustibles being supplied therethrough from a supply conduit 79 to fuel injectors 81, thereby providing firing between banks of tubes 71. A plurality of nested shutters or louvres 83 encase the tubes 71 between said drums, said louvres being so constructed that oxidant under pressure can be driven therebetween towards the downstream end of the chamber defined. An economizer 85 caps the

downstream end of the chamber defined and communicates with an exhaust stack 81.

The structures hereinabove described are each characterized by the provision of bundles of vertical tubes—straight or coiled—carried in individual combustion chambers and surrounded by firing devices. The downcomer systems included in each embodiment of the invention provide optimum circulation, thereby enabling high-speed and high-rate steam generation to be sustained with the supercharged firing arrangements indicated without resort to forced circulation means.

Obviously many modifications and variations of the present invention are possible in the light of the above teachings. It is therefore to be understood that within the scope of the appended claims the invention can be practiced otherwise than as specifically described.

The invention described herein may be manufactured and used by or for the Government of the United States of America for governmental purposes without the payment of any royalties thereon or therefor.

I claim:

1. Apparatus for high-rate steam generation comprising a steam drum disposed horizontally, a water drum disposed parallel to and below said steam drum, a multiplicity of vertical tubes, communicating between said steam and water drums, a plurality of vertical cylindrical casings, said tubes being centrally located in said casings, a plurality of downcomers communicating between said steam and water drums and a plurality of burner rings located within said casings and encircling said tubes, said burner rings being adapted to direct combustible and oxidant under pressure upstream of the casings.

2. Apparatus for high-rate steam generation comprising a steam drum, a water drum, a plurality of casings, a bundle of tubes centrally located in each of said casings and proximately encircled thereby, said tubes communicating between said steam and water drums, annular burner means in each of said casings to propagate flames surrounding each of said bundles of tubes, and a plurality of downcomers external said casings communicating between said steam and water drums.

3. Apparatus for high-rate steam generation comprising a steam drum, a water drum, a plurality of cylindrical casings, a bundle of tubes centrally located in each of said casings and proximately encircled thereby, said tubes communicating between said steam and water drums, annular burner means in each of said casings to propagate flames surrounding substantially the entire length of each of said bundles of tubes, and a plurality of downcomers external said casings communicating between said steam and water drums.

4. Apparatus for high-rate steam generation comprising a steam drum disposed horizontally, a water drum disposed parallel to and below said steam drum, a plurality of casings, a multiplicity of substantially vertical tubes centrally located in each of said casings and proximately encircled thereby, a first header in each of said casings coupling the tubes thereof and said steam drum, a second header in each of said casings coupling the tubes thereof and said water drum, annular burner means in each of said casings to propagate flames surrounding the tubes thereof, and a plurality of downcomers ex-

ternal said casings coupling said steam and water drums.

5. Apparatus for high-rate steam generation comprising a steam drum disposed horizontally, a water drum disposed parallel to and below said steam drum, a plurality of cylindrical casings, a multiplicity of substantially vertical tubes centrally located in each of said casings, a first header in each of said casings coupling the tubes thereof and said steam drum, a second header in each of said casings coupling the tubes thereof and said water drum, annular burner means in each of said casings to propagate flames surrounding the tubes thereof, a plurality of downcomers external said casings coupling said steam and water drums, and a plurality of ducts external said casings coupling the ends of each of said casings.

6. Apparatus for high-rate steam generation comprising a steam drum disposed horizontally, a water drum disposed parallel to and below said steam drum, a plurality of casings, a multiplicity of substantially vertical tubes carried in each of said casings, a first header in each of said casings coupling the tubes thereof and said steam drum, a second header in each of said casings coupling the tubes thereof and said water drum, firing means circumjacent the tubes in each of said casings to propagate flames surrounding the tubes thereof, a plurality of downcomers external said casings coupling said steam and water drums, a plurality of ducts external said casings, a plurality of economizers each communicating with one of said ducts and with the discharge end of one of said casings, and a plurality of blowers each communicating with one of said ducts and with the inlet end of one of said casings.

7. Apparatus for high-rate steam generation comprising a steam drum disposed horizontally, a water drum disposed parallel to and below said steam drum, a plurality of conduits disposed vertically and coupling said steam and water drums, a plurality of casings, clusters of straight tubes carried in each of said casings, a first header carried in each of said casings coupling the cluster thereof and said steam drum, a second header carried in each of said casings coupling the cluster thereof and said water drum, a plurality of firing means circumjacent the tubes in each of said casings to propagate flames surrounding substantially the entire length of the cluster thereof, a plurality of ducts external said casings, a plurality of economizers, each said economizer communicating with the downstream end of one of said firing means with one of said ducts, and a plurality of blowers, each said blower communicating with one of said ducts and with the upstream end of one of said firing means.

8. Apparatus for high rate steam generation comprising a steam drum, a water drum, a plurality of tubular casings spaced and isolated from said drums, a multiplicity of tubes centrally located in each of said casings, a first header in each of said casings coupling the tubes thereof and said steam drum, a second header in each of said casings coupling the tubes thereof and said water drum, firing means circumjacent the tubes to propagate flames surrounding and substantially parallel and coextensive with the length of said tubes carried in each of said casings, a plurality of downcomers external said casings coupling said steam and water drums,

and a plurality of ducts external said casings coupling the ends of said casings.
